THREAD PROTECTOR

Robert R. Irwin, Sewickley, and Harlow W. Culbertson, Edgeworth, Pa.

Application October 29, 1938, Serial No. 237,694

3 Claims. (Cl. 138—96)

Our invention is concerned with protectors such as are normally employed to shield threads from shocks and blows during the transportation and handling of the thread bearing member.

Such protectors commonly have a main body portion composed of a metallic collar which surrounds external shielded threads or is surrounded by internal shielded threads. It has also long been common practice to hold the protector in position relative to said threads by placing between said collars and threads pliant material such as cork, rubber, rope, etc., which firmly engages said collar and threads. Throughout this specification including the claims, "pliant" is used to describe any resilient, yielding, or fibrous material such as rubber, cork, hemp, etc.

The primary object of our hereinafter described invention is to provide a protector in which pliant thread-engaging material is so attached to a collar that very small amounts of it need be used and that the protector may be employed over and over upon numerous thread bearing members without the need for any renewal or adjustment of such material.

Our second object is to provide a protector in which pliant material is so attached to a collar that the material lies along its exposed wall and cushions it against external blows, thus helping to prevent the protector from being jarred loose and unscrewed.

Our third object is to provide a protector in which pliant material is so attached to a collar that some portions of each pliant element engage the shielded threads while other portions of each element lie along the exposed wall of the collar and cushion it against external blows, thus helping to prevent the protector from being jarred loose and unscrewed.

Other objects will be apparent from the ensuing description.

To shield external threads we use a protector which has, briefly, a main body portion composed of a collar which encircles and is spaced from the threads of a threaded member. Pliant elements are so attached to this collar that one or more internal portions of each element lie along the inner wall of the collar for engagement with the shielded threads and thus hold or help to hold the protector in position by a resilient and yielding connection between the collar and threads. Moreover, the elements are so attached that their intermediate parts, between the internal portions, lie along the outer periphery of the collar to form one or more external portions which resiliently and yieldably cushion the protector.

against blows which would otherwise tend to jar it loose and unscrew it. Where each such pliant element passes from the inner to the outer wall of the collar, it is held fixedly in position by means upon the collar, as for example, lugs projecting from the ends of the collar, if the elements pass over its ends, or preferably by the walls of apertures in the collar, if the elements pass through apertures in going from the inner to the outer wall.

To shield internal threads, we merely adapt the above idea to a collar which is surrounded by such threads.

Our preferred embodiments of this invention are disclosed in the accompanying drawings, of which Fig. 1 is a sectional view along the longitudinal axis of a protector; Fig. 2 a side elevation; Fig. 3 a vertical section along the line III—III of Figs. 1 and 2; and Fig. 4 a sectional view, partly in elevation, showing the protector in position upon external threads; Figs. 5 and 6, respectively, a sectional view along the axis and a side elevation of a slightly modified form of protector; and Figs. 7 and 8, respectively, a sectional view along the axis and a side elevation of a protector for use with internal threads.

The embodiment of our invention disclosed in Figs. 1, 2 and 3, for use upon external threads, has a main body portion composed of a circular metallic collar 1 whose inner wall may describe either a right cylinder or a truncated cone, as will be hereinafter described. Through the collar is a row 2 of spaced apertures 3a, 3b, etc., normally even in number, which preferably pass from its inner to its outer wall at oblique angles, as clearly shown in Fig. 3. Also through collar 1 is a second row 4 of spaced apertures 5a, 5b, etc., each of which preferably is in longitudinal alignment with one of the apertures in row 2 and at an oblique angle opposite in direction to that of the aperture in row 2.

A pliant element 6 passes in and out through the apertures in row 2, following the oblique angles of the apertures in the manner disclosed in Fig. 3, to form a series of internal portions 7 and a series of intermediate external portions 8. In a similar manner, a pliant element 9 passes in and out through the oblique apertures in row 4 to form a series of internal portions 10 and a series of intermediate external portions 11. Pliant elements 6 and 9 preferably fit each aperture rather snugly, both to prevent any infiltration of dirt and also to eliminate any movement of the elements relative to collar 1.

One end of collar 1 is preferably provided with

a closure member 12 which stiffens the collar and also prevents the infiltration of dirt. Two integral lugs 13 and 14 protrude outwardly from closure member 12 for engagement by a lever 15 which may be used to screw the protector on or off the shielded threads. A packing ring 16 is preferably placed against closure member 12 in such position that, when the protector is screwed up, the ring is tightly pressed between the shielded threads and closure member 12, to more firmly seat the protector upon the threads and to resist the infiltration of dirt.

Fig. 4 discloses this embodiment of our protector in position upon the tapered external threads 17 of a thread bearing member 18, such as a pipe. As the protector is screwed into position, internal portions 7 of pliant element 6 are wedged between the inner wall of collar 1 and threads 17 and positively and firmly engage the threads. Pliant element 9 is so proportioned that its internal portions 10 are similarly wedged and positively and firmly engage threads 17, it being necessary in the protector shown that element 9 be somewhat larger than element 6 to 25 compensate for the increment in distance between tapered threads 17 and the inner wall of collar 1. Of course, if there is no such increment, the inner wall of collar 1 being spaced uniformly from threads 17, element 9 is normally of the same size as element 6, it being merely requisite that elements 6 and 9 be so proportioned that each firmly and tightly engages threads 18, regardless of the angle between threads 17 and the inner wall of collar 1.

In the protector thus disclosed, it will be noted that threads 17 are fully protected from any external shock, pliant elements 6 and 9 cushioning them from any blows striking collar 1. Moreover, collar 1 is prevented from being jarred loose by such blows, for their shocks are dissipated by the resilient and yielding connection effected by internal portions 7 and 10 and by the cushioning effect of external portions 8 and 11 of said elements. Due to the manner by which these pliant elements are attached to collar 1, a minimum amount of material is used, and this material is firmly fixed in position, so that the protector may be utilized numerous times without necessity for renewal or adjustment of said elements. Of course, as many encircling rows of apertures and pliant elements may be used as is necessary or desirable, while we contemplate the possible use of one alone with some protectors.

Having reference now to the embodiment of our invention shown in Figs. 5 and 6, the main body portion of this protector is composed of a collar 21, generally similar to collar 1, although normally its inner wall is uniformly spaced from threads 17 regardless of their taper. Thus if threads 17 are cylindrical, this inner wall is cylindrical; while if the threads are tapered, its inner wall bears a like taper. Collar 21 is also provided with a row 22 of small spaced apertures 23a, 23b, etc., and spaced from row 22 is a second row 24 of spaced apertures 25a, 25b, etc. A pliant element 26 is passed out through aperture 23a in through an aperture 25b, out through a second aperture 23c, and so on around collar 21, so that there are formed in the element inner portions 27 which lie along the inner wall of collar 21 and engage threads 17 when the protector is in place, and outer portions 28 which lie along the outer wall of collar 21 and cushion it from any shocks or blows. In a similar manner, a pliant element 29 is passed out through aperture 23b

in through aperture 25c, out through aperture 23d, and so on around collar 21 to form thread engaging internal portions 30 and cushioning external portions 31. As in the former embodiment, pliant elements 26 and 29 are firmly held in one position, so that the protector may be used over and over without replacement or adjustment of these elements. Moreover, both thread engaging and cushioning effects are achieved with the use of a small amount of pliant material. Of course, the exact manner in which said elements are woven in and out through the apertures, and the number of elements so used is immaterial to the spirit of my invention. Likewise, the rows of apertures may be increased to three or four, as may be necessary or desirable.

In this embodiment of our invention a closure member 32 attached to collar 21 consists merely of a flange which extends inwardly from the end of the collar. Abutted against closure member 32 is a packing ring 33 which is pressed against the end of threads 17 as the protector is screwed up, thus helping to seat the protector firmly and to prevent the infiltration of dirt.

Fig. 7 discloses a protector for shielding internal threads, such as tapered threads 39, upon a pipe coupler 40. The main body portion of this protector is composed of a collar 41 which is so proportioned that, when inserted within coupler 40, it is spaced from threads 39. Passing through the collar is a row 42 of small apertures 43a, 43b, etc. and spaced from said row is a second row 44 of small apertures 45a, 45b, etc. As in the protectors previously explained, pliant material is passed in and out through these apertures, Fig. 7 portraying the use of pliant elements 46 and 49, which pass, respectively, through the apertures of rows 42 and 44. Thus, there are formed in pliant element 46 a series of external portions 48 which engage threads 39 and in pliant element 49 similarly acting external portions 51. Together these external portions hold the protector in position, and provide a yielding connection between it and threads 39 which absorbs the shocks from blows striking the protector. Moreover, these elements are held firmly in position, so that the protector may be used over and over without the need for renewal or adjustment.

A flange 52 encircles and extends outwardly from collar 41 to form a closure member, and a packing ring 53, pressed between closure member 52 and threads 39, helps to seat the protector firmly in place and to prevent the infiltration of dirt. Two lugs 54 and 55 preferably project from flange 52 for engagement by a lever 56.

We contemplate numerous variations in the embodiments disclosed above, particularly in the manner in which pliant material is placed upon the protectors. Thus, as many encircling rows of apertures as are desirable may be employed, one row alone being sufficient in some protectors. Moreover, pliant material may be woven through these apertures in innumerable ways, while still presenting alternative thread engaging and cushioning portions.

According to the provisions of the patent statutes, we have explained the principle and construction of our invention and have illustrated and described what we now consider to represent its best embodiments. However, we desire to have it understood that, within the scope of the appended claims, the invention may be practiced otherwise than as specifically illustrated and described.

We claim:

1. A protector for external threads of a threaded member comprising a collar adapted to encircle and be spaced from the threads of such member, the wall of this collar being provided with a plurality of apertures, and pliant elements passing in and out through said apertures in such manner that inner portions of said pliant elements lie along the inner wall of said collar for engagement with said threads, while outer portions of said pliant elements lie along the outer wall of said collar and cushion it, said elements being carried by said collar and moved thereby into engagement with said threads. 5
- 10 2. A protector for external threads of a threaded member comprising a collar adapted to encircle and be spaced from the threads of such member, the wall of said collar being provided with a plurality of spaced rows of spaced apertures, and pliant elements which pass inwardly through the apertures in one row and outwardly through the apertures in a second row in such manner that inner portions of said elements lie
- 15 3. A protector for internal threads of a threaded member comprising a collar adapted to be encircled by and spaced from the threads of such member, the walls of said collar being provided with a plurality of apertures, and pliant elements passing in and out through said apertures in such manner that a plurality of circumferentially spaced external portions of said elements lie along the outer wall of said collar for engagement with said threads with their connecting portions extending from one aperture to another inside the collar, said elements being carried by said collar and moved thereby into engagement with said threads. 15 20
